UNITED STATES PATENT OFFICE.

WILLIAM L. BURNER, OF COLUMBUS, OHIO, ASSIGNOR TO THE KILBOURNE AND JACOBS MANUFACTURING COMPANY, OF COLUMBUS, OHIO, A CORPORATION OF OHIO.

DUMP-CAR.

1,245,866.

Specification of Letters Patent.

Patented Nov. 6, 1917.

Application filed December 20, 1915. Serial No. 67,806.

To all whom it may concern:

Be it known that I, WILLIAM L. BURNER, a citizen of the United States, residing at Columbus, in the county of Franklin and State of Ohio, have invented certain new and useful Improvements in Dump-Cars, of which the following is a specification.

The invention relates to dump cars having a bed appropriately mounted thereon for being tilted to dump the same either by rocking on a rocker construction or on a pivot. The invention is applied especially to a car adapted to be dumped by one cylinder and the structure is so formed that a member pivoted on the piston may be swung to one side or the other of the longitudinal center of the car bed by applying power appropriately thereto. The invention therefore makes it possible to dump the car bed in either direction at will by means of a single cylinder.

In the drawings which are hereto attached and hereby made a part of this specification, Figure 1 is an end elevation of the car showing the cylinder in section, the car bed being in normal position; Fig. 2 shows an end elevation of the car with the bed in dumped position.

Referring to the drawings, 1 is a car bed mounted in this instance on the frame 2 by means of the rocker 3 secured to the bottom face of the car bed. Secured likewise on the bottom face of the car bed is the bracket 4 containing the outwardly directed inclined faces 5 and 6 which, if desired, may be serrated as shown at 7.

On the car frame is centrally mounted a cylinder 8 having the piston 9 mounted as usual for reciprocation, the motive force being preferably air. On the upper face of the piston at 10 is pivotally mounted a lifting member 11 which projects upwardly and is adapted to engage one or the other as desired of the faces 5 and 6 of the member 4. The upper edge of said member 11 may be serrated as shown at 12 if serrations are provided on the bracket 4.

In the construction illustrated are shown, on the opposite sides of the car frames, cylinders 13 and 14, the pistons of which are connected by the rod 15; about the middle point thereof rod 15 is engaged with the member 11 in the slot 16 by means of the pin 17, the slot being provided to accommodate the pin to the raised and depressed

positions of the member 11 as shown in the drawings.

Assuming that it is desired to dump the car bed toward the left in the views shown, the piston in cylinder 14 is driven outwardly to swing the member 11 to the position shown in Fig. 1, wherein the upper edge thereof is brought into position to engage the inclined face 6 of the bracket 4 and the piston in cylinder 13 is correspondingly retracted. Now upon admission of air to the cylinder 8 the piston 9 and the member 11 are raised and the car bed is dumped as shown in Fig. 2, and retained in that position until the lading is discharged. Upon the retraction of the piston 9 the car bed rights itself through gravity. Although not illustrated in the drawings, the manipulation of the parts to dump the car bed in the opposite direction will be clearly understood.

The dumping operation could readily be performed by a single cylinder, either 13 or 14 being sufficient; but in such case two packing leathers in the piston would be required, and the rod 15 would also need to be packed. Further in cars of the type illustrated, two air pipes extending along the train would be used, and applicant, for the reasons mentioned, prefers two cylinders.

What I claim as new is:—

1. In a dump car having a car bed mounted thereon to be dumped in either direction, a bracket having inclined faces mounted on the under face of the bottom of said car bed, a dumping cylinder, a tilting member pivoted on the upper face of the piston thereof, and means for positioning said member in engagement with either face to dump the car bed in either direction.

2. In a dump car having a car bed mounted for dumping in either direction, a bracket secured on the under side thereof, a dumping cylinder, a tilting member pivotally mounted on the piston thereof and adapted for engagement with said bracket at either side of the longitudinal center of said car bed, and a cylinder having its piston rod associated with said tilting member to swing the latter into the position desired.

3. In a dump car having a car bed mounted for dumping in either direction, a bracket secured on the under side thereof, a dumping cylinder, a tilting member piv-

totally mounted on the piston thereof and adapted for engagement with said bracket at either side of the longitudinal center of said car bed, and a cylinder having its 5 ton rod associated with said tilting member to swing the latter into the position desired, said tilting member being slotted to accommodate the same in its raised and

lowered positions to the connection with said piston rod.

In testimony whereof I affix my signature in the presence of two witnesses.

WILLIAM L. BURNER.
